HOLD-DOWN CONTROL FOR SLAB SQUEEZERS

William R. Gardner and Merrill V. Hamilton,
Gary, Ind.

Application December 3, 1940, Serial No. 368,404

4 Claims. (Cl. 78—13)

This invention relates to improvements in slab squeezing machines in which large heated steel slabs are compressed along their horizontal edges. During the squeezing operation it is necessary in order to prevent buckling, to provide means for restraining movement of the top and bottom surfaces of the slab. Such means usually consist of a supporting table comprised of a plurality of rollers on which the slab rests and a large hold-down member adapted to be positioned vertically above the heated slab on the rollers.

Conventional slab squeezing machines usually include two large horizontal jaws coextensive in length with the slabs to be acted upon, the action of the jaws being similar to an ordinary bench vise. The jaws are mounted in a manner to permit adjustment to suit various widths of slabs, one being suitably mounted to permit movement forward and backward in a horizontal plane in order to contact the edge of the horizontal plane and exert a squeezing action thereon. Opposed to the moving jaws there is a normally fixed jaw. Power for the moving jaw may conveniently be transmitted from a suitable electric drive through a conventional gear reducer to cams and links in a conventional manner forming no part of the present invention.

One feature of the present invention relates to improvements in existing machines and particularly to a specific hold-down device and means for controlling the extent of movement thereof, and another feature relates to the means for indicating the spacing between the upper surfaces of the slab supporting roller table and the underside of the hold-down device.

The above and other features of the invention will be more fully apparent from a consideration of the following detailed description and claims when read in connection with the accompanying drawings, in which:

Figure 1 is a view partly in side elevation and partly in section of a portion of a conventional type of slab squeezer having my improved hold-down control and the indicating device combined therewith;

Figure 2 is a sectional view on line II—II of Figure 1;

Figure 3 is an enlarged detail section illustrative of an adjustable stop member for accurately controlling the extent of movement of the hold-down;

Figure 4 is an enlarged detail illustrating the hold-down indicator and means for controlling the stops which limit the movement of the hold-down; and

Figure 5 is an elevation at right angles to Figure 4.

Referring in detail to the drawings, the numerals 10 represent a plurality of slab supporting rolls which constitute a conventional type of roll-

er table for supporting the slab S which is to be squeezed by the mechanism. A conventional slab squeezing device includes a normally fixed jaw 12 which, however, is normally adjustable laterally within small limits and a relatively movable jaw 14 powered by a suitable motor drive acting through reduction gearing, levers and links in the conventional manner forming no part of the present invention. Suffice it to say that power means are provided for moving the jaw 14 toward the normally fixed jaw 12 so as to squeeze the slab S therebetween and thus act upon the edges thereof.

In the normal operation of a typical slab squeezer a heated slab S is fed to the squeezer by means of the conveyor table rollers 10 and stopped immediately below the elongated hold-down head 16. The hold-down head is connected to piston rods 18—18 to which are attached suitable pistons (not shown) operating within hydraulic cylinders 20—20. Fluid introduced into the cylinders 20—20 through pipes 22—22 serve to forcibly move the hold-down head 16 into coaction with the top of the slab, as will be understood. The cylinders 20—20 are mounted on a fixed frame member 24 of relatively massive form constituting a component part of a conventional slab squeezing apparatus. The frame member 24 also carries a lifting cylinder 26 within which operates a piston (not shown) having a rod 28 secured thereto which in turn is secured to a yoke 30 carrying a pair of depending rods 32—32, which at their lower ends are connected by pins 34—34 to short links 36—36 which in turn are connected to the hold-down head 16 by pins 38—38 mounted in lugs formed integrally therewith.

The yoke 30 is provided with extensions 40—40 at its ends which coact with adjustable stop members 42—42 which serve as positive means for limiting the downward movement of the hold-down head. Each stop member 42 includes a screw-threaded portion 44 and a shank portion 46, best shown in Figure 3, the shank portion carrying a spline 48 which slidably engages a fixed guide member 50. Each screw shaft 44 engages the internal threads 52 of a nut portion of a worm wheel portion 54. Each worm wheel, best shown in Figure 3, is rotatably mounted in a bearing 56 carried by a casing 58 secured to the frame member 24.

Mounted in spaced relation to the frame member 24 there is an I-bar 60 which near one end carries a motor 62 which is connected by suitable flexible coupling 64 with a shaft 66 carrying worms 68—68 which mesh with the respective worm wheels 54—54 which operate the stops 42—42. As thus arranged it is apparent that the motor 62 is effective to adjust the two stops 42—42 in synchronism so as to cause them to

either approach or recede from the fixed frame member 24. As thus arranged the members 42-42 will serve to limit with precision the extent of the downward movement of the hold-down head 16, it being manifest that when the extensions 40-40 contact the stops 42-42, no further downward movement of the hold-down can take place. It is a further feature of the invention to provide means which visually indicate to the operator as measured in inches and fractions thereof, the space between the underside of the head 16 and the upper supporting surface of the roller table 18. To this end there is provided an indicator of the character best shown in Figures 4 and 5. This includes a standard 70 carrying bearings 72 which rotatably support a shaft 74 having a large indicator dial 76 and a pinion 78 secured thereto. The pinion 78 meshes with rack teeth 80 which are secured to a tubular member 82 which is swivelled on a rod 84 secured to a bracket member 86 extending laterally from the standard 70. A roller 81 serves to hold the rack in mesh with the pinion. The tubular member 82 is slidable on the rod 84 and has secured thereto a Z-shaped member 88, one extremity 90 of which constitutes a fork for engagement with an annulus 92 formed in a collar 94 secured to the upper extremity of the screw shaft 44. As thus arranged it will be manifest that the vertical motion of the screw shaft 44 will be transmitted through the rack and pinion connection described to the indicator disk 76. This disk will be calibrated as indicated by the numerals and graduation marks in Figure 4, to indicate in inches and fractions thereof the distance between the underside of the head 16 and the upper face of the rollers 18 of the roller table. In normal practice this dimension is usually one-fourth inch greater than the thickness of the slab. Mounted for coaction with the indicator dial 76 there is an indicator element 96 having a pointer or other index mark 98 thereon. A spring 100 surrounds the tubular member 82 and reacts against a washer 102 secured against endwise movement with respect to the member 82 by a nut 104 screwed on the end thereof. This spring acts as a cushion to take up slack in the parts. A novel feature of the indicating device is that the dial arrangement can be swivelled on the standard 70 to any suitable position for operator visibility. It will be understood that such adjustment can be secured by swivelling the bearing members 72 about the axis of the tubular member 82.

The herein described means for controlling the downward movement of the hold-down head and for indicating the position thereof constitutes an important improvement on existing machines and contributes materially to efficient functioning and reduces breakage and undue wear to a minimum and prevents costly mill delay, such as frequently occurred in devices not equipped with the present invention. The invention also prevents marking of the slabs, which has often occurred in prior art devices with the accompanying disadvantage that the finished product of the slab frequently had to be rejected.

While we have described quite precisely the specific embodiment of the invention herein illustrated, it is not to be construed that we are limited thereto since various changes may be made by those skilled in the art without departure from the invention as defined in the appended claims.

We claim:

1. Slab squeezing apparatus of the character described comprising a slab supporting table, a hold-down element movable toward and from the latter, stop means for preventing movement of said element beyond a certain predetermined position with relation to said slab supporting table, and an indicator operatively connected with and responsive to movements of said stop for showing the distance between the underside of the hold-down and the upper face of said slab supporting table.

15 2. Slab squeezing apparatus of the character described comprising a slab supporting table, a hold-down element movable toward and from the latter, stop means for preventing movement of said element beyond a certain predetermined position with relation to said slab supporting table, an indicator operatively connected with and responsive to movements of said stop for showing the distance between the underside of the hold-down and the upper face of said slab supporting table, and means providing a swivel mounting for the indicator whereby it can be readily adjusted to facilitate observation by the operator.

30 3. Slab squeezing apparatus of the character described comprising a slab supporting table, a fixed frame member, a hold-down element, means carried by the frame member for moving said hold-down element toward the slab supporting table, means secured to the frame member for retracting said hold-down element, adjustable stops mounted by said frame member effective to limit the extent of movement of said hold-down element toward said table, an indicator operatively connected to said stop comprising a standard supported from said fixed frame member, bearings on the standard rotatably supporting 35 an indicator dial, a pinion on said shaft, a rack meshing with the latter, a swivel guide for the rack, and means for transmitting movement from said adjustable stops to said rack whereby the parts are so coordinated that the indicator 40 will at all times show the distance between the upper face of the slab supporting table and the surface of the hold-down device.

45 4. Slab squeezing apparatus of the character described comprising a slab supporting table, a fixed frame member, a hold-down element, means carried by the frame member for moving said hold-down element toward the slab supporting table, means secured to the frame member for retracting said hold-down element, adjustable stops mounted by said frame member effective to limit the extent of movement of said hold-down element toward said table, an indicator operatively connected to said stop comprising a standard supported from said fixed frame member, bearings on the standard rotatably supporting 50 an indicator dial, a pinion on said shaft, a rack meshing with the latter, a swivel guide for the rack, means for transmitting movement from said adjustable stops to said rack whereby the parts are so coordinated that the indicator will at all times show the distance between the upper face of the slab supporting table and the surface of the hold-down device, and swivel mountings for said indicator whereby it can be adjusted to facilitate observation by the operator.

WILLIAM R. GARDNER.
MERRILL V. HAMILTON.
